UNITED STATES PATENT OFFICE.

HOWARD M. BARBER, OF STONINGTON, CONNECTICUT, ASSIGNOR TO C. B. COTTRELL & SONS COMPANY, OF NEW YORK, N. Y., A CORPORATION OF NEW JERSEY.

SHEET-DELIVERY APPARATUS FOR PRINTING-MACHINES.

1,102,125.

Specification of Letters Patent. Patented June 30, 1914.

Application filed May 28, 1910. Serial No. 563,996.

To all whom it may concern:

Be it known that I, HOWARD M. BARBER, a citizen of the United States, and resident of Stonington, in the county of New London 5 and State of Connecticut, have invented a new and useful Improvement in Sheet-Delivery Apparatus for Printing-Machines, of which the following is a specification.

The object of this invention is to provide 10 certain improvements in the construction, form and arrangement of the several parts of a sheet delivery apparatus for printing machines whereby different lengths of sheets may be positively forwarded to the sheet delivery device by a positive sheet forwarding device adjustable toward and away from the delivery device, and released as their advance edges are engaged by the delivery device. 15 This invention further contemplates an endless sheet delivery carrier driven at a certain speed, a sheet feeding endless tape carrier driven continuously at a higher speed and positive sheet forwarding rolls 20 driven by and at the speed of the tape carrier, said forwarding rolls being adjustable along the tape carrier for causing it to engage and release different lengths of sheets at predetermined times. 25 In the accompanying drawings, the invention is shown in connection with a two revolution rotary cylinder printing machine but it is to be understood that it may be applied to printing machines of various 30 types.

Figure 1 is a partial top plan view of portions of a two-revolution cylinder printing machine having applied thereto the improved sheet delivery apparatus, Fig. 2 is 35 a longitudinal vertical section taken in the plane of the line A—A of Fig. 1, looking in the direction of the arrows, Fig. 3 is a detail view of the drive for the positive sheet forwarding rolls, and Fig. 4 is a detail view of the drive for the sheet feeding endless tape carrier.

In the portion of the printing press herein shown, the form cylinder is denoted by 1 and its impression cylinder by 2. The 40 form cylinder gear 3 is driven from a gear 4 on the drive shaft 5, which shaft is driven from a suitable motor 6. The form cylinder gear 8 meshes with the impression cylinder gear 9. A sheet delivery device is provided 45 for depositing the sheets as they are fed

from the impression cylinder 2, which device may, for instance, be an endless delivery carrier 10, such as that shown, described and claimed in my co-pending application filed June 8, 1909, Serial No. 500878, 50 which endless delivery carrier is driven from the drive shaft 5 through the spur gears 4, 11, bevel gears 12, 13, and shaft 14. This endless delivery carrier 10 may be provided with one or more sets of sheet grippers 15 55 operated at suitable intervals to receive and deposit the sheets.

This present invention is directed to improvements in the means for conveying the sheets from the impression cylinder to the sheet delivery carrier and is constructed, arranged and operated as follows:—A continuously driven endless tape carrier is interposed between the sheet delivery carrier 10 and impression cylinder 2. This tape carrier comprises the tapes 16 which pass around pulleys 17 on the rotary shaft 18 at their inner ends and around pulleys 19 on a rotary shaft 20 at their outer ends.

The sheets as they leave the impression cylinder 2 pass between the sheet guides 21 and the stripper fingers 22 onto the tapes 16. These sheet guides 21 extend outwardly to the point where the sheets are delivered from the endless tape carrier to the endless delivery carrier 10 and they are supported upon cross rods 23, 23. At the outer end of the endless tape carrier, sheet guide fingers 24 are provided below the outer ends of the sheet guides 21, between which guide fingers 24 and guides 21 the sheets are fed from the endless tape carrier to the endless delivery carrier. The endless tape carrier is driven continuously at the speed of the impression cylinder as follows:—A driving belt 25 95 passes at its inner end around a pulley 26 on a cross shaft 27 and at its outer end around a pulley 28 on the cross shaft 20. This shaft 27 is driven through a geared connection 29, 30, from the impression cylinder gear 9. Coacting sheet forwarding rollers 31, 32, are located in proximity to the impression cylinder, the roller 31 being mounted on the shaft 27 and the roller 32 on a cross shaft 33.

A positive sheet forwarding device is provided for engaging the sheets on the endless tape carrier and positively forward the sheets into position to be engaged by the grippers 15 on the endless delivery carrier 110

22

10. This positive sheet forwarding device is adjustable along the endless tape carrier toward and away from the endless delivery carrier whereby different lengths of sheets 5 may be released by the positive sheet forwarding device as the advance edges of the sheets are engaged by the grippers on the endless delivery carrier. This positive sheet forwarding device is constructed, arranged and adjusted as follows:—The forwarding rolls are denoted by 34, 35, and are mounted on the rotary shafts 36, 37, mounted in side plates 38 having pin and slot connections 39, 40, with the side frames 41 of the machine. Each of these elongated slots 40 extends substantially parallel with the tapes 16 of the endless tape carrier and each side plate 38 is provided with two bolts 39 and their nuts for clamping the side plates at 20 any desired position along the tape carrier toward and away from the endless delivery carrier. These sheet forwarding rolls are driven at the same surface speed as the endless tape carrier and the impression cylinder 25 and may be driven by the endless tape carrier as follows:—The shaft 27 is provided with a pulley 41* around which a driving belt 42 passes. This driving belt 42 passes around a pulley 43 mounted on a shaft 44 at a distance outwardly beyond the sheet forwarding rolls. This belt 42 also passes around a pulley 45 on the forwarding roll shaft 37 and another pulley 46 on a shaft 47 mounted in the side plates 38 adjacent to the shaft 37. 30 This arrangement permits the forwarding rolls to be adjusted toward and away from the endless delivery carrier 10 without disturbing the driving connection with the endless tape carrier.

35 40 The sheet guide fingers 24, hereinbefore referred to, are secured at the proper intervals apart to a cross rod 48 mounted in the side plates 38 of the positive sheet forwarding device so that as the sheet forwarding device is adjusted toward and away from the endless delivery carrier, the guide fingers 24 are adjusted with it.

45 In operation, the sheet forwarding rolls 34, 35, are first adjusted at the required distance inwardly from the delivery carrier 10 to permit the rolls to be released from their engagement with the rear edge of a sheet 50 as the advance edge of the sheet is engaged by the grippers 15 on the endless delivery carrier. As the sheet of predetermined length is delivered from the impression cylinder between the guides 21 and stripper fingers 22, it will be engaged by the feeding rollers 31, 32, and fed along the endless tape 55 carrier until the advance edge of the sheet is engaged by the forwarding rolls 34, 35. These forwarding rolls will then positively feed the sheet forward until the advance edge of the sheet is engaged by the grippers 60 15 on the endless delivery carrier. At the

same time, the rear edge of the sheet will pass from between the forwarding rolls thus permitting the endless delivery carrier which travels at a slower speed than the tape carrier and forwarding rolls, to bring 70 the sheets out into position to deposit them in the usual manner.

While I have shown the sheet forwarding rolls as adjustable toward and away from the sheet delivery carrier, it is evident that 75 the carrier itself may be adjusted toward and away from the sheet forwarding rolls and accomplish the same result. It is also evident that any form of sheet delivery carrier may be used in connection with the sheet 80 forwarding device herein described and it is evident that various changes may be made in the construction, form and arrangement of the several parts without departing from the spirit and scope of this invention; hence 85 I do not wish to limit the invention to the exact construction herein shown, but

What I claim is:—

1. In a sheet delivery apparatus for printing machines, a sheet feeding endless tape 90 carrier driven at a certain surface speed and a positive sheet forwarding device located intermediate the ends of the tape carrier, driven at the same surface speed as the tape carrier and adjustable along the same. 95

2. In a sheet delivery apparatus for printing machines, a sheet delivery device and a positive sheet forwarding device, the one adjustable toward and away from the other.

3. In a sheet delivery apparatus for printing machines, an endless sheet delivery carrier driven at a certain speed and a positive sheet forwarding device driven at a higher speed, the delivery carrier and the sheet 100 forwarding device being adjustable the one toward and away from the other. 105

4. In a sheet delivery apparatus for printing machines, a sheet delivery device, a sheet feeding endless tape carrier driven at a certain speed and a positive sheet forwarding device located intermediate the ends of the tape carrier, driven at the same surface speed, the sheet delivery device and the positive sheet forwarding device being adjustable, the one toward and away from the 110 other. 115

5. In a sheet delivery apparatus for printing machine an endless sheet delivery carrier driven at a certain speed, a continuously driven sheet feeding endless tape carrier 120 driven at a higher speed and a positive sheet forwarding device driven at the speed of the tape carrier, the sheet delivery carrier and the positive sheet forwarding device being adjustable the one toward and away 125 from the other.

6. In a sheet delivery apparatus for printing machines, a sheet delivery device, a sheet feeding endless tape carrier driven at a certain speed and a positive sheet forwarding 130

device driven at the same surface speed adjustable along the tape carrier toward and away from the sheet delivery device.

7. In a sheet delivery apparatus for printing machines, an endless sheet delivery carrier driven at a certain speed, a sheet feeding endless tape carrier driven at a higher speed and a positive sheet forwarding device adjustable along the tape carrier toward and 10 away from the sheet delivery carrier.

8. In a sheet delivery apparatus for printing machines, an endless sheet delivery carrier driven at a certain speed, a sheet feeding endless tape carrier driven continuously 15 at a higher speed and a positive sheet forwarding device adjustable along the tape carrier toward and away from the sheet delivery carrier.

9. In a sheet delivery apparatus for printing machines, an endless sheet delivery carrier driven at a certain speed, a sheet feeding endless tape carrier driven at a higher 20

speed, and a positive sheet forwarding device driven at the speed of the tape carrier and adjustable along the same toward and 25 away from the sheet delivery carrier.

10. In a sheet delivery apparatus for printing machines, an endless sheet delivery carrier driven at a certain speed, a sheet-feeding endless tape carrier driven continuously 30 at a higher speed and a positive sheet forwarding device driven at the speed of the tape carrier and adjustable along the same toward and away from the sheet delivery carrier. 35

In testimony, that I claim the foregoing as my invention, I have signed my name in presence of two witnesses, this twenty sixth day of May 1910.

HOWARD M. BARBER.
